UNITED STATES PATENT OFFICE.

ALEXANDRE LAMBLIN, OF PARIS, FRANCE.

RADIATOR FOR MOTOR CARS AND THE LIKE.

Application filed October 5, 1920. Serial No. 414,887.

To all whom it may concern:

Be it known that I, ALEXANDRE LAMBLIN, subject of the King of Belgium, residing at Paris, France, have invented certain new and useful Improvements in Radiators for Motor Cars and the like, of which the following is a specification.

The present invention relates to sundry improvements in cooling radiators for thermal motors. Radiators constructed according to my invention comprise cooling elements such as flat tubes in which the cooling water circulates, these tubes being fixed at three points near their base to three conduits for the inflow and outflow of the water, and means for securely connecting the cooling elements with the water conduits.

This arrangement permits the flat tubes to expand freely under the action of heat when the motor is started.

Several form of the invention are illustratively exemplified in the accompanying drawings in which Fig. 1 is an elevational view of a radiator with certain of the cooling elements omitted; Fig. 2 is a horizontal section on the line *a*—*b* of Fig. 1; Fig. 3 is a substantially central vertical section through Fig. 1; Figs. 4 and 5 are respectively a side elevation and a front elevation of a modified form of radiator; Figs. 6 and 7 are views similar respectively to Figs. 4 and 5 of a still further modified form; Figs. 8 and 9 are respectively a front elevation and a plan view of another modified form of radiator embodying the invention.

1. The cooling radiator shown in Figs. 1, 2 and 3, comprises a reservoir A provided with a filling cap B, and is placed in communication with the top of the engine by a tubular socket C.

The hot water arriving from the engine by the tube C flows into the two lateral tubes D through the apertures E, and into the collectors F through the apertures G extending through the entire height of the radiator. The water is conducted through the cooling elements H thus being cooled. The water then returns to the engine through the tube I and the outlet K.

50 Thus is effected a distribution of hot water throughout the entire height of the radiator by the tubes D. The section of orifice G being smaller than that of the orifice by which the flat tube H communicates with the collector F, it follows that it is possible to regulate as desired the radiator flow by giving

the orifice G a desired sectional form in the course of construction.

The elements of the radiator H are spaced by the tubes L, which maintain them suitably separated for leaving a very free passage for the circulation of the air.

The members H are secured to the collectors F and to the cold water column I by three soldered joints, which are the sole means of attachment, to which easy access is had either by a soldering iron, or by a blowpipe to fix them or to detach them in order to replace them.

The group thus formed is secured in a removable automobile front or frame of the construction disclosed in my Patent Number 1,403,967 issued to me January 17, 1922, such frame being carried by the chassis of the vehicle. The base of the group rests on the base of the frame and is connected thereto by the bolts M. The flange N of the radiator cap engages a corresponding flange of the frame and these two flanges may be secured together by bolts. From this can be observed the facility with which it is possible to withdraw the radiator from its frame to effect the repair or the replacement thereof.

2. Figs. 4 to 7 represent, by way of example, two other embodiments on the same principles, similar to the former, but in these examples the hot water arrives by a central vertical cylinder D and returns to the engine after cooling by two lateral vertical cylinders.

These two embodiments differ from one another only by the shape of the cooling surfaces, which are cylindrical and upwardly convexed in the first form (Figs. 4 and 5), while they are mansard shaped in the second form (Figs. 6 and 7). Figs. 8 and 9 show an embodiment on the foregoing principles which differ from the embodiment of Figs. 1 to 3 only by the shape of the cooling surfaces.

3. The contrivances as shown in Figs. 1 to 9 are applicable to all kinds of radiators, but more especially to radiators of automobiles, wherein the flow of the air is facilitated by the displacement of the radiator.

In all forms of the invention the construction is one assuring free expansion of the cooling elements, simplicity of construction and mounting, and finally ease and rapidity of repair. Moreover by reason of the construction if any one of the elements

is omitted or out of operation the radiator will function satisfactorily with the remaining elements.

Claims:

- 5 1. In a radiator for thermal motors, cooling elements comprising flat tubes through which the water to be cooled circulates, three conduits for the inflow and the outflow of the water, the cooling elements being fixed 10 at three points near their base to the three conduits, and means for securing the connection between the cooling elements and the water conduits.
2. In a radiator for thermal motors, cooling elements comprising flat tubes through which the water to be cooled circulates, two 15

lateral inflow conduits and one intermediate outflow conduit the cooling elements being fixed at three points near their base to the three conduits, each of said lateral conduits 20 comprising a collector F to which said cooling elements are fixed, a water circulation tube D adjacent said collector, said tube D having orifices G providing communication between the tube and the adjacent collector 25 opposite each cooling element.

In testimony whereof I have affixed my signature in presence of two witnesses.

ALEXANDRE LAMBLIN.
